(57) **CLAIM**

The ornamental design for a camera as shown and described.

DESCRIPTION

FIG. 1 is a right side view of a camera showing my new design;

FIG. 2 is a front view thereof;

FIG. 3 is a top view thereof;

FIG. 4 is a bottom view thereof;

FIG. 5 is a back view thereof;

FIG. 6 is a top left side isometric view thereof;

FIG. 7 is a top right side isometric view thereof;

FIG. 8 is a bottom left side isometric view thereof;

FIG. 9 is a bottom right side isometric view thereof;

FIG. 10 is a top back isometric view thereof;

FIG. 11 is a bottom back isometric view thereof; and,

FIG. 12 is a left side view thereof.

The broken lines illustrate the environment of the claimed design and form no part thereof.

1 Claim, 7 Drawing Sheets
